UNITED STATES PATENT OFFICE

2,019,604

COMBINATION HEATING, COOKING, AND
ILLUMINATING STOVE

John H. Grieve, Detroit, Mich.

Application June 12, 1933, Serial No. 675,415

2 Claims. (Cl. 126—4)

The present invention provides an improved stove that is arranged for cooking and baking and with the embodiment of certain features and arrangement of construction, the room or enclosure in which the stove is located is effectively illuminated.

The fuel for the stove may be a suitable oil, manufactured or natural gas, or electricity.

The outstanding advantage of the invention is the fact that due to the scientifically arranged combination of three sources of utility, namely heating, cooking and lighting, the invention presents a new era and transformation from an economical viewpoint, in this particular field of industry.

Further advantages of the invention will be readily apparent during the course of the forthcoming detailed description, throughout the accompanying illustrative drawings, and more particularly pointed out in the appended claims.

With reference to the drawings:

Figure 1 is a front elevation of the complete invention; and

Figure 2 is a side elevation of the same.

Figure 3 is a top plan view of the complete invention.

Figure 4 is a section taken substantially upon line 4—4 of forth-coming Figure 9; and Figure 5 is also a section, taken upon line 5—5 of Figure 9.

Figure 6 is a partial view of the bottom of the device showing the under draft openings therein.

Figure 7 is a rear elevation of the device.

Figure 8 is a transverse section taken substantially upon line 8—8 of Figure 3.

Figure 9 is a longitudinal section taken upon line 9—9 of Figure 3.

Figure 10 is a complete view of the bottom of the device and showing the under air draught control.

The invention comprises a metal casing or enclosure having front panel 1, side panels 2, rear panel 3, top 4 and bottom 5, and with legs formed as at 6.

Fuel chambers 7 are formed by a bottom wall 5, rear wall 8, side walls 9 and a common partition 10, forming thereby two independent chambers. Within said chambers suitable burners 11 are positioned as shown in Figures 8 and 9, with fuel supply lines 12 for the respective burners, being provided.

Within bottom 5 openings 13 are provided so as to accommodate under air draught levers 14, said levers being pivotally secured to bottom 5 as at 15, and it is seen that said under draught

is located directly under the respective burners 11. An oil drip pan 16 is employed for each of said burners and is secured thereto as shown in Figure 9. A door 17 is arranged for each of said fuel chambers and each door being mounted on hinges, and having a suitable door handle 18; said doors being adapted to close the openings in the respective chambers in a substantially tight manner. A plurality of elongated windows 20 are provided in each of doors 17 and are closed with heat-proof transparent material.

Referring more particularly to Figures 8 and 9 it is observed that a double baffle member 21 is provided with its underside forming the ceiling of fuel chambers 7; said member being preferably a suitable hollow casting, provided with openings within the top portion thereof which are adapted to receive stove lids 22 where indicated. There is an opening 23 in the underside of baffle member 21 directly over the burner 11 in each of the fuel chambers 7, and in axial alignment with the corresponding lid opening, so that the heat from the burners will directly contact said lids.

A spacious oven 24 is provided with a suitable door 25, having pulls 26 therefor as shown. The door being pivotally connected to members 27, which are adapted to slide upon rails 28 within the top portion of the device when said door is opened, as indicated by the dotted lines in Figure 8. An opening 29 is arranged in door 25 and is closed by a suitable transparent heat-proof material. The oven is provided with a curved metal back 30, which extends to a point adjacent the bottom of the casing with its lower portion formed as shown at 31. The inner surface back 30 and the portion 31 thereof are provided with a high polish and mirror finish from reflecting surfaces.

Reflectors 32 and 33 are also provided in vertically spaced cooperative relationship on each of the side walls of the casing; the reflectors 33 being opposite the windows in the side walls of the fuel chambers and the reflectors 32 being opposite the windows 40 in the upper side walls of the casing which have their inner surfaces highly polished to a mirror finish.

With special reference to Figure 4 it is seen that a baffle member 34 is arranged within double baffle member 21, and is formed as clearly indicated in Figure 4. Baffle member 34 serves to cause the intensified heat from burners 11 to be directed through openings 23 and lids 22 in baffle plate 21 for a purpose that will be explained later.

Referring to Figures 5, 8 and 9, a screened grate 55

35 is provided and is removably positioned within oven 24 as indicated. Said grate may be readily removed for cleaning purposes. The oven chamber is formed by the back wall 30, the top of the 5 baffle member 21 and side walls 36.

The fumes and objectionable gases are discharged from the interior of double baffle member 21 by means of pipe 37, which leads to the house chimney A, as indicated in Figure 8. In Figure 4 10 pipe 37 is shown as having a funnel shaped end as at 38 communicating with both divisions of the interior of double baffle member 21 so that combustion gases are simultaneously discharged from such compartments.

15 In Figure 10 it is seen that bottom 5 of the device is substantially braced to side panels 2 and rear panel 3 by means of braces 39 as indicated.

An opening 40 is provided in each of the side 20 panels 2 at points directly above the reflectors 33. Openings 41 are provided in the rear and side walls of the fuel chambers 7 directly opposite the reflectors 31 and 33 and are covered with heat-proof transparent material.

25 For baking purposes door 25 is pivotally elevated by means of knobs 26 thereon and is slidably moved inwardly upon rails 28, as clearly shown by the dotted lines in Figure 8, the utensils with the baking material are then placed upon removable grate 35, and the oven door accordingly closed. In Figure 9 it is clearly indicated by the arrows, how the intensified heat from burners 11 is baffled by reason of the lower portion of baffle member 21 and said member having upper 30 and lower walls provide a baffling chamber for each of fuel chambers 7 through openings 23 within the lower walls of said member. An opening or window 29 within door 25 affords adequate 35 facility for viewing the baking within oven 24 admitting of the proper attention required.

40 While oven 24 is entirely enclosed there will be sufficient heat within the upper portion of the stove to provide for ordinary cooking, and for this purpose the elongated openings 42 are arranged within top 4, as clearly indicated in Figure 3.

45 It is understood that the design and exterior finish of the stove is very attractive, and may be placed within the parlor, or in fact within any suitable location of the dwelling, and by virtue of door 25 being adapted to open as previously explained, and when in an opened position as shown by the dotted lines in Figure 8, and by reason of the curved back 30 of the oven, the 50 stove becomes an attractive radiant heater.

55 Referring to Figure 9, the heat from burners 11 will radiate through flue passages 43 and out through opening 40 within each of side panels 2, as shown by the arrows in this view, consequently it is understood that the device provides a very effective heating unit that is capable of heating an entire dwelling consistent with space to be heated and the proportional size of the stove used. The heat is greatly intensified by virtue of reflectors 32 and 33 and back 30.

60 An additional advantage and a novel feature of the invention is the illuminating qualities it

possesses. This is accomplished by means of windows 41 that are located within the respective walls of fuel chambers 7, and again referring to Figure 9 the arrows therein indicate how the light from burners 11 passes through said windows and simultaneously upon reflectors 31 and 33, and the reflection of said light upon reflector 31 will in turn be reflected to back 30 as indicated by the arrows in Figure 8, and when door 25 of oven 24 is closed the last-named light rays will 10 pass out into the room through window 29 within said door. When door 25 is opened then the entire benefit of reflector back 30 is obtained for light into the room.

15 The light rays through windows 41 from burners 11 upon reflectors 33 will in turn be reflected 20 upon reflectors 32 by virtue of uninterrupted flue passages 43, thence outwardly through openings 40 within side panels 2 and into the room. Thus it is understood that the same elements and arrangement thereof effect a combination for the scientific result of both heating and lighting for the intended purpose. It is to be finally understood that the lighting effect of the invention would be confined to the room in which it is 25 located, whereas the heating capacity would be far reaching into other rooms and portions of the dwelling.

Having thus described my invention, what I 30 claim as new is:

1. In a combined cooking and heating stove, 35 an outer casing; means within the lower portion of said casing forming two fuel burning chambers spaced from the rear and side walls of said casing to form therebetween air heating passages; a window in the rear wall and in one of the side walls of each of said fuel burning chambers; a window in each side wall and in the front wall of said casing and vertically spaced above said first-named windows; and a reflector positioned opposite each window; the reflectors opposite the casing windows cooperating with those opposite the fuel burning chambers to reflect the light rays therefrom into the room.

2. In a combined cooking and heating stove, 40 an outer casing; means within the lower portion of said casing forming a fuel burning chamber spaced from the rear and side walls of said casing to form therebetween air heating passages; means within the upper portion of said chamber forming an oven spaced from the rear and side walls of said casing to form therewith continuous of said air passages and including a curved back wall which extends downwardly below and in spaced relation to the rear wall of said fuel chamber and having a reflecting surface in the oven 45 and opposite the fuel chamber whereby light rays from the latter will be reflected toward the front of said oven; a window in the rear wall of said fuel chamber opposite the reflector in said back wall and in each side wall, a window in each side wall of the casing and cooperating reflectors positioned opposite the windows in said side walls whereby light rays from the fuel chamber will be reflected into the room.

JOHN H. GRIEVE.
